[57] CLAIM

The ornamental design for a combined chest of drawers
and open deck or similar article, substantially as shown.

DESCRIPTION

FIG. 1 is a front perspective view of a combined chest
of drawers and open deck showing my new design;

FIG. 2 is a front elevational view;

FIG. 3 is a rear elevational view;

FIG. 4 is a top plan view;

FIG. 5 is a bottom plan view thereof;

FIG. 6 is a right side elevational view thereof; and

FIG. 7 is a left side elevational view thereof.
